NEEDLE POSITIONING MEANS FOR SEWING MACHINES

Reuben Merchant, Nassau, N. Y., assignor to Cluett, Peabody & Co., Inc., Troy, N. Y., a corporation of New York

Application May 13, 1947, Serial No. 747,600

11 Claims. (Cl. 112—219)

1

This invention relates to sewing machines, and particularly to means for stopping them with the needle at either end of its reciprocatory movement. In sewing machines, and particularly those employed in garment factories, it has been customary, when the operator desires to change the direction of sewing or stitching, to stop the machine in a position in which its needle is within the base, so that the fabric being sewed may be pivoted about the needle as a fulcrum, and positioned as desired for the new direction of sewing. The machine itself does not always stop with the free end of its needle within the base, and when it does not the operator manually turns the hand wheel on the main shaft sufficiently to cause the free end of the needle to enter the base far enough to enable the needle to be used as the pivotal axis. This often requires an extra manual effort on the part of the operator, which is time consuming in that the hand must be moved from the work to the hand wheel and then back again in order to move the needle into the base. It is also desirable at intervals to stop the machine with the needle in its upper or retracted position where its free end is out of the base in order to facilitate the change of a bobbin within the base.

An object of the invention is to provide an improved sewing machine, with which the main shaft may normally be stopped while the free end of the needle is within the base of the sewing machine, which may be easily applied to existing types of sewing machines without greatly altering the present construction thereof, which may be rendered effective or ineffective as desired, and which will be relatively simple, compact, convenient, practical and inexpensive.

Another object of the invention is to provide an improved sewing machine, with which the needle may be stopped or positioned with the free end of the needle either within the base or out of the base as may be desired, with which the selection as to the stopping position may be changed at will in a simple manner, with which inoperativeness of the stopping or positioning mechanism due to a dead center position may be avoided in a simple manner, with which the needle may be stopped automatically and selectively at either end of its reciprocation without any material increase in the operating time of the machine, which will not materially interfere with the normal manipulation of the sewing machine, and which will not require the use of the operator's hands in effecting positioning of the needle.

Various other objects and advantages will be

2

apparent from the following description of one embodiment of the invention, and the novel features will be particularly pointed out hereinafter in connection with the appended claims.

5. In the accompanying drawing:

Fig. 1 is a front elevation of part of a conventional sewing machine having attached thereto an electromagnetic device for causing the machine to stop with the free end of its needle either within or out of the base, as may be desired;

Fig. 2 is a transverse, sectional elevation of the same on a larger scale than that of Fig. 1, the section being taken approximately along the line of 2—2 of Fig. 1;

15. Fig. 3 is a circuit diagram for the same;

Fig. 4 is a schematic front elevation, on a smaller scale than Fig. 1, of the operating means for a sewing machine of the type shown in Fig. 1, and having incorporated therewith means for

20 controlling the activity of the needle positioning means provided on the apparatus shown in Fig. 1; and

Fig. 5 is a side elevation of a part of the mechanism shown in Fig. 4, as viewed from the line 25 5—5 of Fig. 4.

In the illustrated embodiment of the invention, the sewing machine may be of any conventional type such as one having a base 1, an up-standing pedestal 2 thereon, an overhanging arm 3 at the upper end of the pedestal 2, a reciprocating needle bar 4 at the free end of the overhanging arm 3, and a needle 5 depending from the lower end of the needle bar 4 and entering and leaving the base as the needle bar 4 reciprocates vertically in Fig. 1.

The needle bar 4 is reciprocated vertically by suitable mechanism (not shown) within the arm 3, and this reciprocating mechanism includes a main shaft 6, Fig. 2, which extends horizontally in Fig. 1 through the arm 3. This main shaft extends beyond the arm 3 and pedestal 2, to the right in Fig. 1, and carries a hand wheel 7 which may be grasped and turned by the operator when one desires to slowly move the needle bar 4. The shaft 6 also carries the pulley 8 by which it may be driven, and an endless belt 9 passes over the pulley 8 for driving the latter and through it the main shaft 6. Within the base 1 is the usual shuttle (not shown) having a bobbin, and the shuttle is operated by mechanism within the base 1 in timed relation to movement of the needle bar 4. This is a typical sewing machine which is purchased in the open market and per se these interior details of the sewing machine are not a part of this invention.

The belt 9 may be driven from any suitable power source, but a mechanism for that purpose is shown in Fig. 4 in which the belt 9 operates over a driving pulley 10. This pulley 10 is driven through a clutch and brake mechanism 11 from a motor 12 or other continuously rotating source of power. The clutch and brake mechanism 11 by which the motor 12 may be coupled to or uncoupled from the pulley 10 is a commercial unit obtainable in the open market and the details of this mechanism are also per se not part of this invention. This clutch and brake mechanism commonly includes a disc rotating with the pulley 10, which is shiftable in one direction against a rotating disc which is driven by the motor 12, and in the opposite direction against a stationary brake plate disc. While this disc rotates with the pulley 10, it is shiftable in opposite directions along the axis of rotation through a pin 13 which extends through an elongated slot in the housing 14, and this pin 13 is received in the fork of a bell crank lever 15 that is pivoted at 16 on a relatively fixed bearing arm 17. Thus by rocking the lever 15, the pulley 10 may selectively be coupled to the motor 12 or yieldingly urged against a brake surface within the mechanism 11. A spring within the clutch and brake mechanism 11 normally urges the pin 13 to the left in Fig. 4 and causes an application of the brake and an uncoupling of the pulley 10 from the motor 12.

To cause an operation of the sewing machine the operator normally depresses a foot lever 18 which is connected by a link 19 to the free end of the lever 15. This rocks lever 15 to cause a driving coupling of the pulley 10 to the motor 12 and a release of the brake. The mechanism so far described is a conventional construction now in use, and I have applied thereto apparatus for stopping the main shaft 6 in a position to have the free end of the needle 5 selectively either within the base or out of the base. The main shaft 6 extends outwardly beyond the pulley 8 in Fig. 1, and fixedly mounted thereon is a bar 20 which, at equal distances from the shaft 6, carries polar terminals 21 and 22, one at each end. The bar 20 and the terminals 21 and 22 are made of a metal or other material which may be permanently magnetized. Such a metal when placed in a magnetic field will become a permanent magnet and retain a definite polarity. There are many such metals or alloys available in the open market, for making permanent magnets one of them which is particularly suitable being an alloy of aluminum, nickel, cobalt and iron.

In the particular example the bar 20 and the terminals 21 and 22 are so magnetized that the terminal 22 corresponds to the "north" pole of a permanent magnet and is designated (Fig. 2) by the symbol or letter "N" printed thereon, and the other terminal 21 has the magnetism of a magnetic "south" pole and has the letter or symbol "S" printed thereon. The outer faces of the terminals 21 and 22 are circularly convex, the center of curvature substantially coincident with the axis of rotation of the shaft 6. A U-shaped iron core 23 (Figs. 1 and 2) is mounted on the base 1 in any suitable manner, such as by a post 24, see Fig. 1, and the gap in the U receives the bar 20 and terminals 21 and 22. The inside faces of the arms of the U-shaped core 23, at their free ends, are concave as at 25, see Fig. 2. The core 23 is of good magnetic flux-conducting material such as soft iron, which will not retain any large amount of mag-

netism when out of a magnetic field. Surrounding the base or cross part of the core 23 is an electromagnet or solenoid coil 26, and when electric current passes through this coil 26, a strong magnetic field will be set up, and the lines of force thereof will pass along the frame or core 23 between the free ends of the arms thereof, and then through the terminals 21 and 22 and the bar 20 to complete the magnetic circuit. Direct current is employed for the coil 26.

When the direct current flowing in the coil 26 travels in one direction through that coil, it will cause the upper arm of that core 23 to have one polarity at its free end, such as "north" polarity, and the free end of the lower arm of the core 23 then has the opposite or "south" polarity. It is well-known that like poles of a magnet repel and unlike poles attract, and, therefore, if the upper arm of the core 23 at its free end corresponds to a "north" pole and the end piece 22 is a north pole, there will be a repelling magnetic torque between them, and at the same time, since the free end of the lower arm of core 23 and the end piece 21 both have a "south" polarity, a similar repelling torque action will take place between them. This double repelling action at both ends of the bar 20 will exert a rotary torque on the main shaft 6 and will cause shaft 6 to rotate until the end piece 21 is uppermost and the end piece 22 lowermost. This rotation will then stop because as soon as the end piece 22 is less than a quarter revolution from the free end of the lower arm of the core 23, there will be an attraction between the unlike poles of the lower arm of core 23 and the end piece 22. A similar attraction also then occurs between the unlike poles of the end piece 21 and the upper arm of the core 23.

When the end piece 21 becomes approximately aligned with the upper arm of core 23, and the end piece 22 becomes approximately aligned with the lower arm of core 23, the shaft 6 will be magnetically held in that position by the attraction between the unlike poles of the core 23 and the bar 20. Thus the current in the coil 26 will cause the main shaft 6 to turn through such part of a half revolution of the shaft, in one direction or the other, as will place the free end of the needle bar 4 at one end of its reciprocation. If the current is sent through the coil 26 in the opposite direction, then the lower arm of the core 23 becomes the "north" pole and the upper arm of core 23 becomes the "south" pole, and the bar 20 will then be moved into a position into which the needle bar 4 is stopped at the opposite end of the reciprocation. Thus, by merely controlling the direction of the current through the coil 26, one may cause the needle bar 4 to move selectively into a position occupied at either end of its reciprocation, and remain there until the coil 26 is demagnetized.

The circuit for controlling the current through coil 26 is illustrated diagrammatically in Fig. 3 in which the ends of the coil 26 are connected by wires 27 and 28 to the contacts 29 and 30 respectively of a reversing switch 31. The other terminals of the reversing switch 31 are connected to line wires L-1 and L-2. One of these line wires, such as L-2, has in series therein a manually operable overtravel switch 32 by which current may be supplied to or disconnected from the coil 26. Thus by closing the switch 32, a magnetic torque will be applied to the main shaft 6 which will rotate the shaft 6 through not more

than a half revolution into a position in which the needle bar is at one end or the other of its reciprocation, depending upon the position of the reversing switch 31. The position in which the needle stops may be changed by merely operating switch 31. An overvoltage protector of any suitable design may be connected between wires 27 and 28 so as to be in parallel to coil 26.

Referring particularly to Figs. 4 and 5, the switch 32 is positioned for operation by a foot pedal or lever 33 which is pivoted at 34 on a suitable base 35 which also mounts the switch 32. The switch 32 has an operating element or stem 36 which, when depressed, causes a closing of the circuit, and a spring 37, Fig. 5, returns the switch element 36 to its circuit breaking position when the pressure of lever 33 on the end of element 36 is released. The switch 32 preferably should be one in which overtravel is possible, i. e. the movable switch element 36 can continue movement in the same direction to a substantial extent after the circuit has been closed, for a reason which will appear presently. A rod 38 extends loosely through the free end of lever 33, and its lower end carries a head 39. A helical compression spring 40 surrounds the lower end of the rod 38, with its upper end abutting the underface of the lever 33 and its lower end abutting against the head 39. When the lever 33 is depressed it will compress the spring 40 and pull downwardly on rod 38 with a force depending on the compression of the spring 40.

The upper end of the rod 38 passes loosely through a lateral extension 41 on a split clamp 42 which is secured by clamping on the free arm of the bell crank lever 15. Nuts 43 and 44 are provided on the upper end of the rod 38 at opposite sides of the extension 41 so that they provide spaced abutments on the rod 38 through which motion is transmitted between the rod 38 and the lever 15. The nuts 43 and 44 preferably should not be tightened against the extension 41 but should have a slight spacing so that there will be sufficient freedom of pivoting of the rod 38 in the extension 41. When lever 33 is depressed it will, during the first part of its movement, operate the switch 32 and close the circuit to the coil 36, and at the same time spring 40 will be compressed.

Compression of spring 40 will cause a downward pull on rod 38, but this pull is insufficient, in the early part of the movement, to overcome the spring within the clutch and brake element 11 that urges lever 15 counterclockwise in Fig. 4, but if the lever 33 is further depressed, the switch 32 remains closed and the pressure on spring 40 increases until it overcomes the opposing action of the spring within the clutch and brake element 11, and it then rocks the bell crank lever 15 clockwise in Fig. 4 and causes a coupling of the pulley 10 to the motor 12. The motor 12 will then rotate the pulley 10 and through the belt 9 will rotate the shaft 6 while the magnetic torque is applied to the bar 20 by the magnetic field created by the current in coil 26. The main shaft will thus be operated by the motor 12 with the aid or opposition of the magnetic torque, and this action need be continued only momentarily until the shaft 6 is out of any magnetic dead center in which it may have stopped.

In operation, the operator performs the usual sewing operation by starting the sewing machine through a depression of the foot lever 18, which

rocks the lever 15 and causes a coupling of pulley 10 to the motor 12, with concurrent release of the brake action on pulley 10. When the operator completes a line of sewing and wishes to change the direction of sewing, she will release the foot lever 18 which causes an uncoupling of the pulley 10 from motor 12 and an application of braking force to the pulley 10. At the same time that the foot pedal 18 is released, the operator depresses foot lever 33 through a part only of its movement, but which is sufficient to operate switch 32 and cause delivery of current to coil 26. Assuming that switch 31 has first been adjusted to a position in which the current will pass in coil 26 in a direction to cause the stopping of the needle bar 4 with the lower or free end of the needle 5 within the base 1, it follows that when the switch 32 is closed in this manner, the magnetic action will normally stop the decelerating shaft 6 when the free end of the needle 5 is within the base 1. The magnetic torque on the decelerating shaft 6 will retard, or assist rotation of the shaft as necessary to cause the shaft to stop with the free end of the needle within the base 1.

In other words, operation of switch 32 will cause shaft 6 to stop or move into a position normally where the free end of the needle is within the base, and the operator may then pivot the fabric being sewed, on the needle as a fulcrum into a new position for sewing, whereupon the operator releases foot pedal 33 and depresses foot pedal 18. This again starts the machine for sewing and disconnects current from coil 26 so that the machine operates normally again. If the shaft 6 should happen, as it does very infrequently, to stop in a magnetic dead center position where the "north" pole represented by end piece 23 is in perfect alignment or center with respect to that arm of the core 23 which corresponds to the "north" pole of the electromagnet, the repulsion between those "north" poles would be equal in both directions and we would have what has been termed above a magnetic dead center position.

When that happens the operator merely depresses pedal 33 to a further extent, beyond that which closed the switch 32, and this increases the pressure on spring 40 until it overcomes the spring in the element 11, with the result of recoupling the pulley 10 to the motor 12. This causes sufficient rotation of the shaft 6 by the motor 12 to carry it out of dead center position, and as soon as the movement again starts the operator partially releases the foot lever 33, which releases lever 15 so that the motor 12 is at once uncoupled from pulley 10, but since switch 32 is still closed the magnetic motor will move the shaft 6 into the normal stopping position, in which the free end of the needle 5 is within the base 1.

If one desires to elevate the needle, and hold it elevated while the machine is idle, to facilitate changing of the bobbin within the shuttle in the base 1, one merely reverses the switch 31 and partially depresses foot lever 33 to close switch 32, without rocking lever 15. This will cause the shaft 6 to turn, under the magnetic torque created by the coil 26 on bar 20, for approximately a half revolution and stop with the free end of the needle 5 above the base 1. If now the foot pedal 33 is fully released, switch 32 will be opened and the shaft 6 will remain in that position with needle 5 entirely above base 1.

If, when the foot lever 33 was depressed to operate switch 32 and cause an elevation of the needle 5 above base 1, the bar 20 happened to be in full magnetic dead center position, the operator would merely further depress foot lever 33 momentarily to recouple motor 12 to pulley 10 long enough to move the bar 20 out of dead center position, and then return foot pedal 33 to the mid-position while the magnetic torque from coil 26 rotated shaft 6 to retract the needle 5 from the base. If the operator desires to stop the sewing operation with the needle elevated, the reversing switch 31 is operated into the proper position, and when stopping is desired, pedal 18 is released to uncouple motor 12 from pulley 10 and pedal 33 partially depressed to energize coil 26 and apply the torque that stops the shaft 6 with the needle elevated.

Alloys useful as the material of permanent magnets are referred to, for example, in "Engineering Encyclopedia" by F. D. Jones and published by Industrial Press, and also in a book entitled "Engineering Alloys" by Woldman and Dornblatt which refers to a permanently magnetizable alloy 72181 as made by General Electric Co. called "Alnico" and formed of 20% nickel, 12% aluminum, 5% cobalt, and 63% iron. These are merely examples of suitable alloys and are not exclusive.

It will be understood that various changes in the details, materials and arrangements of parts which have been herein described and illustrated in order to explain the nature of the invention, may be made by those skilled in the art within the principle and scope of the invention as expressed in the appended claims.

I claim:

1. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing to pivot the fabric upon the needle, which comprises the combination with said machine of an electromagnetic power device for operating said shaft into a position in which the free end of said needle is within said base, and means for rendering said power device selectively effective and ineffective.

2. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination with said machine of a polarized permanent magnet part, an electromagnetic part, one of said parts being mounted on said shaft for rotation therewith, the other of said parts being mounted adjacent said one part for exerting on the latter a rotary torque urging said shaft into its position occupied when the free end of said needle is within said base, an electric circuit leading to said electromagnetic part, and a switch included in and controlling said circuit.

3. In a sewing machine of the type having a

reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination with said machine of a polarized permanent magnet part, an electromagnetic part, one of said parts being mounted on said shaft for rotation therewith, the other of said parts being mounted adjacent said one part for exerting on the latter a rotary torque urging said shaft into its position occupied when the free end of said needle is within said base, an electric circuit leading to said electromagnetic part, a switch included in and controlling said circuit, and a reversing switch in said circuit.

4. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, but selectively operable to cause stopping with the needle out of said base to facilitate change of bobbins within said base, which comprises the combination with said machine of a polarized permanent magnet part with diametrically opposite opposed poles, an electromagnetic part having similarly disposed opposed poles, one of said parts being mounted on said shaft for rotation therewith, the other of said parts being mounted adjacent said one part for exerting on the latter a rotary torque urging said shaft into its position occupied when the free end of said needle is within said base, an electric circuit leading to said electromagnetic part, and a reversing switch included in and controlling said circuit, whereby by directing current through said electromagnetic part in one direction said shaft will be stopped with its needle within the base, and by directing it through that part in the opposite direction said shaft will be stopped with its needle outside of said base.

5. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination with said machine of a polarized permanent magnet part, an electromagnetic part, one of said parts being mounted on said shaft for rotation therewith, the other of said parts being mounted adjacent said one part for exerting on the latter a rotary torque urging said shaft into its position occupied when the free end of said needle is within said base, an electric circuit leading to said electromagnetic part, and a switch included in and controlling said circuit.

6. In a sewing machine of the type having a

fromagnetic power device for operating said shaft into a position in which the free end of said needle is within said base, switch means for rendering said power device selectively effective and ineffective, and means selectively operable while said electromagnetic power device is effective for operating said clutch and brake to cause further movement of said shaft.

6. In a sewing machine of the type having a reciprocating needle, a base into and out of which the free end of the needle moves, once for each reciprocation, a main shaft operatively connected to said needle to cause the latter to reciprocate and making one revolution for each complete reciprocation of said needle, and a driving device for said shaft, that improvement for causing said machine to stop normally with the free end of the needle within said base and enable an operator of the machine when changing the direction of sewing on fabric, to pivot the fabric about the needle as a fulcrum, which comprises the combination with said machine of a polarized permanent magnet part, an electromagnetic part, one of said parts being drivingly coupled to said shaft for rotation therewith, the other of said parts being mounted adjacent said one part for exerting on the latter a rotary torque urging said shaft into its position occupied when the free end of said needle is within said base, an electric circuit leading to said electromagnetic part, a switch included in and controlling said circuit, and means selectively operable while said switch is closed to deliver current to said electromagnetic part for also causing rotation of said shaft sufficiently to carry said permanent magnet part out of any magnetic dead center position in which it may stop.

7. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination with said machine of a polarized permanent magnet part, an electromagnetic part, one of said parts being drivingly connected to said shaft for rotation therewith, the other of said parts being mounted adjacent said one part for exerting on the latter a rotary torque urging said shaft into its position occupied when the free end of said needle is within said base, an electric circuit leading to said electromagnetic part and a switch included in and controlling said circuit.

8. In a sewing machine of the type having a main shaft, a needle reciprocatingly operated by said shaft, a base into and out of which the free end of said needle moves during its reciprocation and once for each rotation of said main shaft, a source of power, a driving connection between said source and shaft and including a clutch and brake by which when the source of power is rendered ineffective, the brake will be operated to retard further movement of said shaft, that improvement for causing said machine to stop normally with the free end of said needle within said base to enable an operator of the machine, when changing the direction of sewing on fabric, to pivot the fabric upon the needle, which comprises its combination with said machine, clutch

and brake, of a polarized permanent magnet part, an electromagnetic part, one of said parts being drivingly coupled to said shaft for rotation concurrently therewith, the other of said parts being mounted adjacent said one part for exerting on the latter a rotary torque urging said shaft into the position that it occupies when the free end of said needle is within said base, an electric circuit leading to said electromagnetic part, a switch included in and controlling said circuit, and means selectively operable while said switch is closed for operating said clutch and brake to cause movement of said shaft sufficiently to carry it out of any magnetically dead center in which it may stop.

9. In a sewing machine of the type having a reciprocating needle, a base into which enters the free end of the needle, once for each reciprocation, and a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination with said machine of a polarized permanent magnet part, an electromagnetic part, one of said parts being drivingly coupled to said shaft for rotation therewith, the other of said parts being mounted adjacent said one part for exerting on the latter a rotary torque urging said shaft into its position occupied when the free end of said needle is within said base, an electric circuit leading to said electromagnetic part, a switch included in and controlling said circuit, and means selectively operable while the switch is closed for moving said shaft sufficiently to cause relative movement between said parts out of any magnetic dead center position in which said shaft may stop.

10. In a sewing machine of the type having a reciprocatable needle, a base into and out of which the free end of the needle moves in its reciprocation, a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination of an electromagnetic power device having a relatively movable polarized permanent magnet part for operating said main shaft into a position in which the free end of the needle is within said base when said main shaft is inoperative, a drive motor connected to said main shaft to operate it for sewing and having therein a slip clutch, a lever for rendering said clutch effective and ineffective, two manually operated controls connected to said lever one of which may be used to operate the machine in the usual manner, a switch having a control element operable by the other of said controls between an off position when that control is released, and closed circuit position when that control is operated, said switch element having an overtravel while in the closed circuit position to enable continued movement of said other control after the switch element reaches closed circuit position, and an electric circuit including said switch and said electromagnetic power device, whereby said one control will normally be used for controlling sewing operations, and the other control will be

used when one desires to stop the needle within said base, said other control having three operative positions through which it moves consecutively, the first position being the idle position, the second position being ineffective to reclutch the motor to the main shaft and the third position being effective to reclutch said motor to said shaft, and operation of said other control to its said second position will energize said electromagnetic power device to stop the needle within said base, and operation to its third position will keep said circuit closed and also cause reclutching of said motor to said main shaft to move said shaft out of any dead center condition of said power device.

11. In a sewing machine of the type having a reciprocatable needle, a base into and out of which the free end of the needle moves in its reciprocation, a main shaft operatively connected to said needle and making one revolution for each complete reciprocation of said needle, that improvement for causing said machine to stop normally with the free end of the needle in said base to enable an operator of the machine, when changing the direction of sewing, to pivot the fabric upon the needle, which comprises the combination of an electromagnetic power device having a relatively movable polarized permanent magnet part for operating said main shaft into a position in which the free end of the needle is within said base when said main shaft is inoperative, a drive motor connected to said main

5 shaft to operate it for sewing and having therein a slip clutch, a lever for rendering said clutch effective and ineffective, two manually operated controls connected to said lever one of which may be used to operate the machine in the usual manner, a switch having a control element operable by the other of said controls between an off position when that control is released, and closed circuit position when that control is operated, said switch element having an overtravel while in the closed circuit position to enable continued movement of said other control after the switch element reaches closed circuit position, and a reversing switch in series in said circuit 15 whereby one may selectively stop the needle in its elevated position instead of entering the base or move the needle to said elevated position from its position in said base.

REUBEN MERCHANT.
